TOBACCO STICK

Daniel M. Boone, Lumberton, and Stephan C. Boone, Charlotte, N. C.

Application March 19, 1947, Serial No. 735,722

7 Claims. (Cl. 294—5.5)

1

This invention relates to a tobacco stick and more especially to the tobacco stick having means for securing the butt ends of the tobacco leaves in position without the aid of a string or other means such as impaling means and the like.

It is an object of this invention to provide a metallic tobacco stick comprised of two parts, one telescoped within the other and having spaces between the inner and outer portions for receiving the butt ends of tobacco leaves whereby the stems of the tobacco leaves are gripped or pinched between the inner and outer members of the tobacco stick and are held in position without any danger whatever of leaves becoming separated from the stick during a curing operation for the reason that as the diameter of the stems decrease in the curing operation the weight of the inner member will cause it to move downwardly and grip the leaves and take care of any loss in the diameter of the stems of the tobacco leaves.

Some of the objects of the invention having been stated, other objects will appear as the description proceeds and taken in connection with the accompanying drawings, in which—

Figure 1 is an elevation of the tobacco stick with the central portion thereof broken away and showing the leaves of tobacco in position;

Figure 2 is a vertical sectional view taken along the line 2—2 in Figure 1;

Figure 3 is the end elevation looking along line 3—3 in Figure 1;

Figure 4 is a view similar to Figure 3, but showing a modified form of the inner member;

Figure 5 is an isometric view of the entrance end of the tobacco stick and showing parts broken away;

Figure 6 is a plan view of the entrance end of the inner portion of the stick omitting the outer portion;

Figure 7 is a sectional plan view taken along the line 7—7 in Figure 3 and omitting the tobacco leaves;

Figure 8 is an enlarged elevation of the right hand end of the tobacco stick shown in Figure 1;

Figure 9 is a longitudinal sectional view of the left hand end of the tobacco stick in Figure 1 and taken along line 9—9 in Figure 2 and omitting the tobacco leaves;

Figure 10 is a view similar to Figure 5, showing the modified inner member of the stick.

Referring more specifically to the drawings the numeral 10 indicates an outer channel member having a top wall and vertically disposed side wall portions which are turned inwardly at each edge as at 11 and 12 thus forming a slot 13 between the

proximate edges of the inturned portions 11 and 12.

Disposed within the confines of the member 10 is an inner member 15. This member 15 is formed preferably from sheet metal and has an upper portion 16 which is bent inwardly upon itself and has a downwardly projecting portion 17 formed from the downwardly projecting legs thereof which are flared outwardly as of 18 and 19 and the raw edges are bent upon themselves as at 20 and 21 to form a finished edge. These diverging portions 18 and 19 loosely fit in the slot 13, giving sufficient clearance for tobacco leaves to pass between the portions 18 and 19 and the proximate edges of the inturned portions 11 and 12.

This member 15 at one end thereof is slotted as at 25 and which slot is loosely penetrated by a pin 26 mounted in the vertical side walls of the member 10 and spanning the distance between the side walls. The other end of the member 15 is beveled as at 27 and 28 to assist in guiding the tobacco leaves between the edges of the member 15 and the interior of the member 10. The member 15 has near each end thereof the lower portions of the diverging portions 18 and 19 cut away to prevent the member 15 from resting on the tiers in a tobacco barn and, thus, the cause weight of the tobacco leaves to be supported by the ends of the member 10.

At the end opposite the member 10 where the pin 26 occurs, the inturned portions 11 and 12 are bent upwardly against the interior of the side walls of the member 10 as at 35 and 36 to thus enlarge the slot 13 and to assist in guiding the stems of the tobacco leaves into position inside the member 10 and on the exterior the member 15.

In Figures 4 and 10, a slightly modified form of the inner member is shown, this inner member 40 being indicated by reference character 40 and instead of having a planar upper portion bent upon itself, it is made from a piece of sheet metal bent to provide a flat upper surface 41 and inwardly converging portions 42 and 43 which meet each other as at 44 and then diverge as at 45 and 46 and its lower edges are turned inwardly upon each other as at 47 and 48 and present a finished edge.

This inner member 40 in a modified form is secured by pin 26 in the same manner as previously described for member 15 and at its other end the top portion 41 is beveled as at 50 and 51 to assist in guiding the stems of the tobacco leaves in between the inner and outer members. This member 40 also has its diverging lower portions

45 and 46 cut away as at 52 in the same manner as is shown in Figure 5 for the member 15 to thus prevent this member 15 from engaging the tiers on which the sticks are supported and thus throwing the weight of the stick and the tobacco leaves on the outer member 10 as previously described in the first form of the invention.

The tobacco leaves are indicated broadly by reference characters 55 and their butt or stem portions are indicated at 56.

In placing the leaves of the tobacco in position, the end of the tobacco stick having the pin 26 therein is supported on a suitable support and with one hand the operator can support the free end of the tobacco stick and feed the tobacco stems of 56 of the tobacco leaves 55 in between the inner member 15 or 40 as the case may be and the exterior member 10 to where they will be pinched between the upper portion of the member 15 or 40 as the case may be and an intermediate portion of the stems will be disposed between the inturned portions 11 and 12 and the diverging portions 18 and 19 or the diverging portions 45 and 46 as the case may be, thus not only to pinch the tobacco leaves between the portions of the member 15 or 40 as the case may be and the inner walls of the member 10 but also to pinch them between the inturned portions 11 and 12 and the diverging portions 18 and 19 or 45 and 46 of the inner member 15 or 40 as the case may be.

As the tobacco leaves dry during a curing process, there will be a tendency for the inner member 15 or 40, as the case may be, to sag downwardly which will tend to cause the top planar portion of the member 15 to press the stems against the inturned portions 11 and 12 but to also in the modified form shown in Figures 4 and 10, this pinching effect will take place earlier because the inwardly converging portions 42 and 43 will tend to press the intermediate portions of the tobacco stems against the proximate edges of the inturned portions of 11 and 12.

In the drawings and specification there has been set forth a preferred embodiment of the invention, and although specific terms are employed, they are used in a generic and descriptive sense only, and not for the purposes of limitation, the scope of the invention being defined in the claims.

We claim:

1. A stick for supporting tobacco leaves in a tobacco barn for a curing operation comprising a tubular member having a slot along its lower edge and being open at both ends, an inner member disposed within the tubular member and being pivotally supported at one end by the tubular member, the other end of the inner member being pointed to assist in directing the stems of tobacco leaves into the space between the interior of the tubular member and the exterior surface of the inner member, the portions of the tubular member adjacent the free end of the inner member being turned upwardly away from the free end of the inner member to provide space for receiving the stems of tobacco leaves inserted between the inner member and the interior surface of the tubular member.

2. A stick for supporting tobacco leaves in a tobacco barn for a curing operation comprising a tubular member having a slot along its lower edge and being open at both ends, an inner member disposed within the tubular member and being pivotally supported at one end by the tubular member, the other end of the inner member

being pointed to assist in directing the stems of tobacco leaves into the space between the interior of the tubular member and the exterior surface of the inner member, the portions of the tubular member adjacent the free end of the inner member being turned upwardly away from the free end of the inner member to provide space for receiving the stems of tobacco leaves being inserted between the inner member and the interior surface of the tubular member, the ends of the inner member being cut away to prevent their engaging tiers which support the ends of the tubular member.

3. A tobacco stick for supporting leaves of tobacco comprising an inner member and an outer member, the outer member being tubular and having a slot extending from one end to the other along its lower edge, the inner member being disposed within the outer member and having laterally projecting portions along its top edge and also having laterally projecting portions along its lower edge whereby the stems of tobacco leaves can be fed into the slot in the outer member and passed between the projections on the inner member and the inside surface of the outer member to confine the stems during a curing operation.

4. A tobacco stick for supporting leaves of tobacco comprising an inner member and an outer member, the outer member being tubular and having a slot extending from one end to the other along its lower edge, the inner member being disposed within the outer member and having laterally projecting portions along its top edge and also having laterally projecting portions along its lower edge whereby the stems of tobacco leaves can be fed into the slot in the outer member and passed between the projections on the inner member and the inside surface of the outer member to confine the stems during a curing operation, the slot in the outer member being widened at one end and the inner member being pointed at the same end to assist in guiding the stems of the tobacco leaves between the inner and outer members.

5. A tobacco stick for supporting leaves of tobacco comprising an inner member and an outer member, the outer member being tubular and having a slot extending from one end to the other along its lower edge, the inner member being disposed within the outer member and having laterally projecting portions along its top edge and also having laterally projecting portions along its lower edge whereby the stems of tobacco leaves can be fed into the slot in the outer member and passed between the projections on the inner member and the inside surface of the outer member to confine the stems during a curing operation, one end of the inner member having a vertically disposed slot therein and a pin mounted in the outer member and penetrating said slot to allow vertical movement of the inner member relative to the outer member, the slot at the end of the outer member remote from said pin being widened and the free end of the inner member being beveled on each side thereof to assist in guiding the stems of tobacco leaves between the inner and outer members.

6. A tobacco stick comprising inner and outer members, the outer member being tubular and substantially rectangular in cross-section and having a slot extending longitudinally along the lower portion thereof from one end of the same to the other, the inner member being substantially T-shaped in cross-section and having its

lower portion of greater width than its intermediate portion and extending through the slot in the outer member, means in one end of the outer member for pivotally supporting one end of the inner member, the other end of the outer member having its slot widened and the free end of the inner member being restricted in width to assist in the feeding of stems of tobacco leaves between the inner and outer members, the lower portions of the ends of the inner member being cut away to allow downward movement of the inner member relative to the outer member when the ends of the outer member are resting on tier poles in a tobacco barn.

7. A tobacco stick comprising inner and outer members, the outer member being tubular and substantially rectangular in cross-section and having a slot extending longitudinally along the lower portion thereof from one end of the same

to the other, the inner member being substantially triangular in cross-section and having its lower portion of greater width than its intermediate portion and extending through the slot in the outer member, means in one end of the outer member for pivotally supporting one end of the inner member, the other end of the outer member having its slot widened and the free end of the inner member being restricted in width to assist in the feeding of stems of tobacco leaves between the inner and outer members, the lower portions of the ends of the inner member being cut away to allow downward movement of the inner member relative to the outer member when the ends of the outer member are resting on tier poles in a tobacco barn.
